UNITED STATES PATENT OFFICE.

GEORGE EPAM BLIZIOTIS, OF NEWARK, NEW JERSEY, ASSIGNOR TO WESTINGHOUSE ELECTRIC & MANUFACTURING COMPANY, A CORPORATION OF PENNSYLVANIA.

WAVE COMPENSATION ON TELEPHONE LINES.

Application filed September 8, 1923. Serial No. 661,553.

This invention relates to transmission lines and particularly to lines used for telephonic transmission.

It is an object of this invention to provide means for protecting telephone instruments from the effects of inductive action by neighboring lines such as electric lighting and power lines.

It is a further object of this invention to so arrange telephone transmission lines that the impulses due to the inductive action of neighboring lines will produce in the receiving circuit equal and opposite effects which cancel one another.

These and other objects will be made apparent through the further description of my invention which is illustrated in the accompanying drawings, wherein the single figure illustrates diagrammatically a telephone line embodying my invention.

In this figure, 1 is a source of telephone current. A switch 2 enables the energy from this source to be impressed upon either of two circuits 3 and 4. These are the primary circuits of a pair of transformers 5 and 6. The circuit 3 is inductively connected by the transformer 5 to a line circuit 7, which is a complete metallic circuit including the secondary coil of the transformer 5, two line wires and a primary coil 8 at the receiving end of the line. The primary circuit 4 is inductively connected by the transformer 6 to a line circuit 9 which is a complete metallic circuit including two line wires and a primary coil 11 at the receiving end of the line. The primary coils 8 and 11 form parts of one transformer 12 having a single secondary coil 13 which supplies the receiving circuit 16.

The drawing shows in dotted lines a number of neighboring wires 14, 15 which are intended to represent parts of any disturbing lines, such as electric lighting lines, high-tension power lines, trolley wires or any other sources of disturbance that might cause noises in the telephone receivers. In the operation of the device, any inductive influence emanating from the wires 14 produces current simultaneously in both the circuits 7 and 9. The primary coils 8 and 11 are wound upon the transformer 12 in such relative directions that the flux due to the induced current in line 7 will oppose the flux due to the current simultaneously induced in the line 9. In the same way, when

the wires 15 exercise an inductive influence, the current induced in one of the two line circuits 7 and 9 will produce a flux in the transformer 12 that opposes that produced by the current in the other of said line circuits. Thus, whether the extraneous influence comes from the one side of the telephone line system or the other, the disturbances set up in the transformer 12 are opposite in direction and the electromotive forces caused in the secondary 13 will also be opposed. These disturbances, being opposite in effect, tend to cancel each other. In order that the cancellation shall be as nearly complete as possible, provision is made for so adjusting the primary coils 8 and 11 that if the influence of either one tends to predominate, this tendency will be corrected by such adjustment. Thus the electromotive forces induced in the receiving circuit by extraneous, disturbing influences can be made to cancel one another and no noise will be produced in the telephone instruments because of such disturbances.

The invention is applicable to any transmission system using telephone lines in pairs, whether these lines are used simultaneously for carrying two or more messages, or used singly, as illustrated in the drawing. The single use of the lines has been indicated by providing the switch 2, but it is obvious to those skilled in the art that any of the standard ways of arranging the sending end of a telephone transmission system may be substituted for the source 1 and the switch 2 without departing from the spirit and scope of this invention.

While I have illustrated but one embodiment of my invention it will be apparent to those skilled in the art that various changes and modifications may be made in the apparatus illustrated without departing from the spirit and scope of my invention, as set forth in the appended claims.

I claim as my invention:

1. A transmission system including two neighboring complete metallic lines, means at the sending end for impressing current on at least one of said lines, a common receiving circuit and means at the receiving end for inductively connecting said lines to said common receiving circuit in inductive opposition to one another with respect to a field resulting from an external circuit.

2. A transmission system including two

neighboring complete metallic lines, means at the sending end for impressing current on at least one of said lines, a common receiving circuit, a transformer at the receiving end including a secondary in said receiving circuit and two primaries one in each of said lines, said primaries being inductively opposed to one another with respect to a field resulting from an external circuit.

3. A telephone system including two neighboring complete metallic lines, a power line adjacent thereto, means at the sending end for impressing current on at least one of said telephone lines, a common receiving circuit, means at the receiving end for inductively coupling said telephone lines to each other and to the common receiving circuit, said coupling being so directed that an electromotive force in one of said telephone lines due to inductive influences of the power line will oppose an electromotive force in the other line induced by the same influences.

25 4. A transmission system including two neighboring telephone lines, means at the sending end for impressing current on at least one of said lines, a common receiving circuit, an inductively related power line, means at the receiving end for inductively coupling said telephone lines to each other

and to the common receiving circuit, said coupling being so connected that impulses in said lines due to inductive influences of the power line will cause opposing electro-motive forces in said coupling circuit, and means for adjusting said coupling whereby said opposite electromotive forces may be made equal.

5. In a transmission system two neighboring complete metallic lines, a source of telephone current, means for impressing energy from said source upon either of said lines, the other of said lines being then disconnected from said source, a receiving circuit remote from said source common to said lines, an adjacent power circuit, two primaries one in each of said lines, said primaries being in inductive relation to each other and wound to produce fluxes in opposite directions in response to influences acting upon both of said lines from said power circuit, a secondary in said receiving circuit in inductive relation to both of said primaries and means for independently adjusting the coupling between each of said primaries and said secondary.

In testimony whereof, I have hereunto subscribed my name this 20th day of Aug., 1923.

GEORGE EPAM BLIZIOTIS.
